UNITED STATES PATENT OFFICE.

ABRAHAM JOHANNES VAN STOCKUM, OF RIJSWIJK, NETHERLANDS.

SUBMARINE MINE.

1,159,300.

Specification of Letters Patent.

Patented Nov. 2, 1915.

Application filed March 28, 1913. Serial No. 757,418.

To all whom it may concern:

Be it known that I, ABRAHAM JOHANNES VAN STOCKUM, subject of the Queen of the Netherlands, residing at Rijswijk, Kingdom 5 of the Netherlands, have invented certain new and useful Improvements in and Relating to Submarine Mines, of which the following is a specification.

This invention relates to submarine mines 10 of the kind adapted to be maintained in position by an anchoring device to which the mine is connected by a cable and which are arranged to be exploded when struck by a vessel or other heavy floating object.

15 The object of the present invention is to provide an improved mine of this description which shall automatically remain immersed at approximately any predetermined depth in the water and shall be perfectly 20 safe when floating at or near the surface and furthermore shall not be liable to be affected by the explosion of other mines in the immediate vicinity.

The invention is illustrated in the accompanying drawings of which—Figure 1 is a view in sectional elevation showing the mine proper and the anchoring device supporting the mine. Fig. 2 is a view in sectional elevation at right angles to the view shown in 30 Fig. 1, and Figs. 3 and 4 are views illustrating the method of setting the mines into position.

Referring now to the drawings, the mine proper consists of a spherical shell or casing 35 and a cylindrical portion B which is closed at its lower end by means of a cone-shaped base b. The shell A is a substantial and watertight structure containing the explosive charge, primer and igniting device, the 40 cylindrical and conical portions B and b being of lighter construction and in open communication with the surrounding water. The portions B and b of the mine serve to inclose and protect the depth regulating 45 gear located therein, the cylindrical portion B being provided on its outer surface with a number of blades or vanes 9.

These blades or vanes serve to effect the 50 submersion of the mine to the predetermined depth, the currents in the water to which the mine is exposed imparting a rotary motion to the blades 9 and the casing B to which they are attached, this motion being transmitted to the depth regulating gear, as 55 will be hereinafter explained. For this pur-

pose the blades or vanes may be of any suitable curved or helical form so as to cause the mine, in the oblique position it assumes when floating in the current, to respond readily to the flow of the water, or the blades 60 or vanes may be hinged at their inner edges to the cylindrical portion B of the mine so as to open outward when moving in the direction of flow of the current and to turn inward so as to lie flat against the cylindrical portion B when advancing against the current, the position of the blades 9 being successively and automatically altered in this manner as the mine rotates.

At the lower end of the spherical shell or 70 casing A of the mine a circular aperture is provided in which a movable disk or piston 10 is located being provided with watertight packing of any suitable description, such for instance as a rubber diaphragm inclosed 75 by a perforated cover 11. The piston 10 is provided with a central stem 12 which is adapted to slide within a sleeve or bushing 13 rigidly connected to the cover 11 so as to be attached to the body of the mine. Surrounding the sleeve 13 is a sleeve 14 carrying two bevel wheels 15 and 16 which are maintained in position thereon longitudinally by means of nuts but are free to rotate 80 on the sleeve 14. The sleeve 14 is connected 85 to the stem 12 of the piston 10 by means of a pin 21, passing through slots provided in the fixed sleeve 13 so as to allow the stem 12 and the sleeve 14 a slight amount of play 90 in a vertical direction.

Rigidly attached to the sleeve 13 are two clutch plates 19 and 20, the upper plate 19 being located above the upper bevel wheel 15 and the lower plate 20 being underneath the lower bevel wheel 16. The faces of the 95 clutch plates and the bevel wheels which are opposite to one another are provided with radial ribs or clutch surfaces so that either of the bevel wheels 15 or 16 may be locked to the corresponding clutch plates 19 or 20 100 and thus to the body of the mine by an upward or downward displacement of the piston 10.

In the space between the two bevel wheels 15 and 16 a sleeve 17 attached to the supporting frame 18 of a cable drum a is loosely mounted on the sleeve 14 and in order that the rotation of the sleeve 17 relative to the sleeve 14 may be as frictionless as possible 105 suitable bearings (not shown in the draw- 110

ings) may be provided. Mounted on the frame 18 and engaging both the bevel wheels 15 and 16 is a third bevel wheel 22 which is keyed to its shaft 23 and connected to the 5 shaft 24 of the cable drum α by a suitable reduction gear.

The gear consists of the two equally large and rigidly connected wheels 25 and 59 eccentrically and rotatably mounted on the 10 shaft 23. The wheel 25 meshes with the stationary ring 60 provided with inwardly extending teeth, while the wheel 59 meshes with the wheel 61; the latter being rotatably mounted on the shaft 23. This wheel 61 15 meshes also with the wheel 62, which is rigidly connected with the wheel 63, while the said wheels 62 and 63 are rotatable about a pivot connected to the supporting frame 18. The wheel 63 now meshes with the wheel 64, 20 connected to the shaft 24 of the cable drum.

The upper part of the cable 1 by means of which the mine is attached to the anchoring device is wound on the drum α so that the rotation of the drum α causes the mine to 25 rise or descend according to whether the drum is being rotated in the one or the other direction.

The cable connecting the mine and the anchoring device passes out of the conical base b through a hawse pipe 28 mounted on the frame 18. The depth regulating gear above described serves to maintain the mine at the predetermined depth being operated in the following manner by the rotation of 30 the mine in a constant direction:—The opposing forces to which the piston 10 is subjected when the mine is immersed are the tension in the cable 1 acting downward, which is equal to the constant buoyancy of 35 the mine and a force acting upward due to the pressure of the water at a depth to which the mine is submerged. The pull of the cable is transferred to the piston 10, as the whole mechanism arranged in the casing B 40 hangs on the piston stem. This may be seen from Fig. 2 of the drawing. The piston receives the pressure of the water as the water can freely enter the casing B through the hawse pipe mounted on the frame 18. 45 The water pressure must therefore be transferred to the air in the casing B, which will be compressed, while the pressure is transferred to the piston 10 (the cover 11 of the piston being perforated). Now the 50 buoyancy being a constant force, whereas the pressure of the water increases with the depth of immersion it is evident that at a certain definite depth the two forces will counter-balance each other, the buoyancy predominating at a less depth and the pressure of the water predominating at a greater depth. Consequently, if the area of the piston 10 is such that the equilibrium between the two forces above mentioned occurs at 55 the desired depth of immersion, the piston 60

will move upward relative to the sleeve 13 whenever the mine is too deeply immersed. When the mine that is to say, the casings A and B, rotates, the piston 10 with piston rod 12 rotates with the mine, whereby the clutch plates 19 and 20 also rotate with the piston rod. The rest of the mechanism in the casing B hangs, as stated, on the piston rod, but does not rotate therewith. In case now the clutch plate 19 or 20 engages the wheel 15 75 or 16, one of these wheels 15 or 16 will be rotated, so that the wheel 22, the gear mechanism and the drum is rotated.

When the mine is not immersed to the desired depth the lower bevel wheel 16 which 80 is rotatably mounted on the sleeve will be engaged by the lower clutch plate 20 and thereby caused to rotate as the mine rotates, this rotation being transferred by means of the bevel wheel 22 to the cable drum α effects 85 the winding of the cable on the drum α so as to cause the mine to increase its depth of submersion. If, however the mine is too deeply immersed the piston 10 will move upward relative to the sleeve 13 so as to 90 cause the upper bevel wheel 15 to rotate with the mine, causing the cable drum α to be rotated in the opposite direction so as to slacken the cable and allow the mine to rise nearer the surface of the water. 95

It will be understood that the force exerted on one or other of the bevel wheels will in the first instance tend to make the supporting frame 18 together with the cable drum α rotate with the mine, thereby tending to twist the cable without having any other effect upon it.

In order to overcome this difficulty the cable drum α is arranged in its frame 18 eccentrically within the parts B and b of the 105 mine, as far as possible removed from the axis of the revolution of the mine so that the mine tilts very decidedly away from a vertical position and a rotating motion of the drum α and its co-operating parts is prevented by the weight of the cable drum and frame 18, the center of gravity of the drum always tending to take up a position b, the axis of the mine owing to the oblique 110 position which the mine assumes owing to 115 the influence of the eccentrically disposed weight but mainly due to the action of the water currents.

In order to prevent the cable from fouling when it is wound on the drum, the latter is 120 arranged to be movable in a longitudinal direction along the shaft 24, the shaft and drum being connected together by a key 65 and keyway 66 as shown in Fig. 1 of the drawings. Surrounding the shaft 24 and secured to the frame 18 a screw-threaded sleeve 56 is provided fitting within the hollow and internally threaded spindle 55 of the drum α , so that as the cable drum α rotates with its shaft 24 the drum is caused to 125 130

alter its position longitudinally to such an extent that the cable does not overlap as it is wound on the drum *a*, the pitch of the threads on the sleeves 55 and 56 being equal to the diameter of the cable. In order to still further insure this action, the drum *a* may be provided with a helicoidal groove 57, adapted to accommodate the convolution of the cable.

10 The length of the sleeve 56 relative to the shaft 24 is so chosen that the cable can always run on or off the drum passing in a straight line through the hawse pipe 28 (as illustrated in Fig. 1). The length of the 15 sleeve 56 must therefore be at least as great as the length of the drum. In practice the sleeve is a little longer, so that the drum cannot run off the sleeve. The shaft 24 is therefore at least twice as long as the drum 20 and about twice as long as the sleeve 56.

The construction and operation of the mechanism for effecting the explosion of the mine is as follows:—On the lid of a casing *g* containing the explosive charge, the primer 32 and the detonator 31, a striker 29 is mounted, pivoted at 33 and provided with suitable guide plates 58. A rod 36 is connected at one end to the striker 29 at a short distance above the pivot of the latter the 30 other end of the rod 36 being connected to a piston 35 working in a small cylinder formed in a recess of the mine shell and rendered watertight by an india rubber disk and ring or perforated cover 34 so that when the mine 35 is submerged to the necessary depth the pressure of the water on the piston 35 tends to force the striker 29 downward so as to bring the nipple 30 on to the detonator 31 thus effecting the explosion of the charge.

40 A spring 37 is provided adapted to abut against the inner face of the piston 35 and oppose the action of the pressure of the water to a certain extent so as to render the mine absolutely safe against explosion when 45 it is floating at the surface or only slightly submerged.

In order to prevent the striking mechanism being operated so long as the mine remains untouched, the striker is adapted to be 50 held in its upright position by a retaining lever or trigger 38, one extremity of which engages with the upper end of the striker 29 the lever 38 being pivoted at 39 to two lugs attached to the base of a recess formed 55 at the upper end of the spherical shell or casing. The lever 38 is provided with a counterweight 52 and is maintained at its normal position by means of a spring 51. The lever 38 is arranged to be moved upward so as to release the striker 29 by a 60 spindle 40, connected thereto and passing through the base of a recess in the mine casing.

The release of the striker 29 in the manner 65 above described is arranged to be effected

when the mine is struck by a heavy body by means of a set of contact levers or feelers 47 which are arranged symmetrically around the mine and pivoted thereon adjacent to the base of the mine as indicated at 48 being 70 counterbalanced by the projecting ends 50. The feelers 47 are curved so as to correspond to the shape of the mine from which they are separated by a short distance, the feelers being provided with guides 53. The 75 upper ends of the feelers extend within the recess at the upper end of the mine casing, a corresponding set of small bell-crank levers being arranged around the spindle 40 and pivotally mounted on a frame 42. One arm 80 of the bell-crank levers 44 engages with the extremities of the feelers 47, the other arms of the levers 44 engaging with the under surface of a collar on the spindle 40 so that should any of the feelers 47 be moved toward the shell of the mine the spindle 40 is raised and the striking mechanism is released in the manner already described. The spindle 40 passes through the guide 43 formed in the frame 42 and the base 41 of 90 the recess, a water tight joint being insured by means of an india-rubber disk secured at its center portion between a collar on the spindle 40 and a nut, the outer edge of the rubber disk being secured between the base of the 95 recess and a flange on the frame 42. It should be observed that the feelers 47 cannot be actuated except by bodily contact as a suddenly excessive pressure in the water due to an explosion in the vicinity of the mine tends 100 to force the spindle 40 downward toward the base of the recess, so that the striking mechanism cannot possibly be released or the mine exploded by counter-mining.

The arrangements for retaining or anchoring the mine at the desired position are indicated at C in the drawings and comprise a heavy casing *c* of circular form having a conical central depression to accommodate the lower part of the mine, and a cylindrical portion *d*, around which a main cable drum *b*¹ provided with cheeks is arranged, the lower portion of the cable being wound on this drum. In order to render the drum *b*¹ readily rotatable a suitable number of guide 110 rollers 3 are provided, the drum being retained in position by an annular plate *e* secured to the top of the casing by means of stud bolts and nuts 2, 2¹. These bolts are indicated at 2, 2¹ in Fig. 3, are arranged closely adjacent to one another in a circular series and form a guide for the cable passing from the drum *b*¹. Adjacent to the guide bolts 2¹ but on the inside of the drum 115 and arranged in a slot 5 formed in the wall *d* of the casing is a double armed pawl 7 which is pivotally mounted on the casing and provided with a weighted arm 8. The inner surface of the drum *b*¹ is provided 120 with teeth 6 so as to constitute a ratchet 125

wheel which may be engaged by either of the arms of the pawl 7.

This pawl is designed to lock the cable drum in all positions except that of Fig. 3.

5 The anchoring device is mounted on rollers 4 so as to be capable of being readily moved together with the mine to the position required for launching as shown in Fig. 1 of the drawings. When the mine is 10 launched the mine and anchoring device separate, the former remaining at the surface of the water owing to its buoyancy and the anchoring device sinking by reason of its own weight. The stress thereby 15 exerted on the cable causes the anchoring device to be rotated through an angle of 90° so as to bring the casing of the device into a vertical position in which the pawl 7 is disengaged from the teeth 6 on the inner side 20 of the cable drum b^1 . The latter being therefore free to rotate the cable unwinds, allowing the anchoring device to descend as shown in Fig. 3. On reaching the bottom 25 the anchoring device falls over on one or other of its flat sides and the pawl 7 engages with the teeth on the cable drum b^1 and thus prevents further unwinding of the cable. The depth regulating device then comes into action causing the mine to descend to its proper depth and maintaining it at this depth of submersion in the manner 30 already described.

It will be understood that various modifications may be made in the construction 35 and arrangement of the parts herein described and illustrated without exceeding the scope of the invention.

I claim as my invention:—

40 1. The combination in a submarine mine of mechanism for raising and lowering said mine, and means operated by the rotation of the mine for operating said mechanism.

45 2. The combination in a submarine mine of mechanism for raising and lowering said mine, means dependent upon the rotation of the mine for operating said mechanism, and means for automatically controlling the operation of said mechanism.

50 3. The combination in a submarine mine of mechanism for raising and lowering said mine, means dependent upon the rotation of the mine for operating said mechanism, and means for automatically controlling the operation of said mechanism in accordance 55 with the depth of immersion of said mine.

4. The combination of a submarine mine, an anchoring device therefor, a cable connecting the anchoring device to the mine, and means dependent upon the rotation 60 of the mine for varying the distance between the mine and said anchoring device.

5. The combination of a submarine mine, an anchoring device therefor, a cable connecting said anchoring device to said mine, means operated by the rotation of said mine 65

for operating said mechanism, and automatic means for controlling said mechanism in accordance with the depth of immersion of the mine.

6. The combination in a submarine mine 70 of a mechanism operated by the rotation of the mine for varying the depth of immersion of said mine, and means dependent upon the pressure of the water at the depth of immersion for controlling said mechanism. 75

7. The combination in a submarine mine of an anchoring device therefor, a cable connecting said anchoring device to said mine, mechanism for varying the length of cable 80 between said anchoring device and said mine, means dependent upon the rotation of the mine for effecting the operation of said mechanism, and means dependent upon the pressure of the water at the depth of 85 immersion for controlling the operation of said mechanism.

8. The combination in a submarine mine of a buoyant member, a non-buoyant member, a cable connecting said members and 90 means dependent upon the rotation of the buoyant member for varying the length of said cable.

9. The combination in a submarine mine of a buoyant member, a non-buoyant member, a cable connecting said members, a number 95 of blades or vanes located on said buoyant member for effecting the rotation thereof, and means for utilizing the rotation of said buoyant member to vary the depth of 100 immersion thereof.

10. The combination in a submarine mine of a non-buoyant member, a buoyant member, and means controlled by the buoyancy and rotation of the latter member and by 105 the pressure of the water at the depth of the immersion for controlling the distance between the two members.

11. The combination in a submarine mine of a non-buoyant member, a buoyant member, blades or vanes located on the latter member, a cable connecting said members, mechanism operated by the rotation of said 110 buoyant member for varying the length of cable separating the two members, and an 115 automatic device for controlling the operation of said mechanism.

12. The combination in a submarine mine of a non-buoyant member, a relatively rotatable buoyant member, a cable connecting said 120 members, a cable drum located within said buoyant member, mechanism for transmitting the rotation of said buoyant member to said cable drum, and a device dependent upon the depth of immersion for automatically controlling said mechanism. 125

13. In a submarine mine the combination of a buoyant member, firing mechanism therefor, means permanently influenced by the pressure of the water at the depth of 130

immersion for operating said firing mechanism, contact levers located on said buoyant member, and means operated by said contact levers for releasing said firing mechanism.

14. The combination in a submarine mine of a buoyant member, means for automatically maintaining said member at a predetermined depth of immersion, a body of explosive contained within said member, mechanism for firing said explosive, means permanently influenced by the pressure of water at the depth of immersion for operating said firing mechanism, and contact levers located on said member for releasing said firing mechanism.

15. The combination in a submarine mine of a buoyant member, a cable drum secured thereto, means dependent upon the rotation of said member for rotating said drum, mechanism for transmitting the rotation of said member to said drum, and means dependent upon the internal and external pressures on said member when immersed for controlling the operation of said mechanism.

16. The combination in a submarine mine of a buoyant member, a cable drum attached to said member, means for effecting the rotation of said member when immersed in a current of water, a device for directly transmitting the rotation of said member to said drum, a device for transmitting the rotation of said member to said drum in the reverse direction of rotation, a movable abutment subject to the opposing internal and external pressures upon said member, and means operated by said abutment for rendering one or other of said devices operative.

17. The combination in a submarine mine of a buoyant member, a non-buoyant member, a cable drum located on said non-buoyant member, and means dependent upon the angular disposition of said non-buoyant member for controlling the operation of said cable drum.

18. The combination in a submarine mine of a buoyant member, an anchoring device therefor of substantially disk-like form, a cable drum located in said anchoring device, and means for preventing the rotation

of said cable drum when the axis of the anchoring device is substantially vertical.

19. The combination in a submarine mine of a buoyant member, a non-buoyant member, a cable connecting said members, means operated by the rotation of said buoyant member for varying the length of cable separating the two members, and means for preventing the rotation of said cable. 55 60

20. In a submarine mine the combination with a rotatable buoyant member, an anchoring device therefor, a gearing element connected to said rotatable buoyant member, a second gearing element pivotally mounted 65 upon said buoyant member, a cable drum rotated by said second gearing element, and means dependent upon gravity for maintaining the axes of said cable drum and of the second gearing element stationary relative to said buoyant member. 70

21. The combination in a submarine mine of a buoyant member, an anchoring device therefor, means operated by the rotation of said buoyant member for causing the latter 75 to approach said anchoring device and means dependent upon the relative buoyancy of said member and of the water pressure at the depth of immersion for arresting such approach. 80

22. The combination in a submarine mine of a submerged buoyant member, an anchoring device therefor, a body of explosive contained in said buoyant member, firing mechanism for said body of explosive, means for 85 operating said firing mechanism and influenced by the pressure of the water at the depth of immersion; a device for arresting the operation of said firing mechanism, contact levers on the outside of said member for 90 releasing said arresting device, and means operated by excessive pressure of the water for maintaining said arresting device operative.

In testimony whereof I have hereunto set 95 my hand in presence of two subscribing witnesses.

ABRAHAM JOHANNES VAN STOCKUM.
